(57) **CLAIM**

We claim the ornamental design for a garbage disposal shell, as shown and described.

DESCRIPTION

FIG. 1 is a perspective view of a garbage disposal shell, showing our new design;

FIG. 2 is a front view of the claim design shown in FIG. 1; FIG. 3 is a rear view of the claimed design shown in FIG. 1;

FIG. 4 is a top view of the claimed design shown in FIG. 1; FIG. 5 is a bottom view of the claimed design shown in FIG. 1;

FIG. 6 is a side view of the claimed design shown in FIG. 1; and,

FIG. 7 is another side view of the claimed design shown in FIG. 1.

The broken lines represent portions of the garbage disposal shell that form no part of the claimed design. The dash dot broken lines shown in the figures depict boundaries of the claim and form no part thereof.

1 Claim, 5 Drawing Sheets
